[57] CLAIM

The ornamental design for padded sleeve for holding an electronic device within a carrying case, as shown.

DESCRIPTION

FIG. 1 is a perspective view as seen from top, front and right sides of my padded sleeve for holding an electronic device within a carrying case showing my new design, the broken dash lines representing stitching.

FIG. 2 is a top plan view thereof;

FIG. 3 is a front elevational view thereof;

FIG. 4 is a right side elevational view thereof, the left side view being a mirror image;

FIG. 5 is a rear elevational view thereof; and,

FIG. 6 is a bottom plan view thereof.
